CLAIM

The ornamental design for an earpiece, as shown and described.

DESCRIPTION

FIG. 1 is a front right perspective view of an earpiece showing our new design;

FIG. 2 is a right side elevational view thereof;

FIG. 3 is a left side elevational view thereof;

FIG. 4 is front elevation view thereof;

FIG. 5 is a rear elevational view thereof;

FIG. 6 is a top plan view thereof; and,

FIG. 7 is a bottom plan view thereof.
